Primary Examiner — Vy Koenig*Assistant Examiner* — Omeed Agilee(74) *Attorney, Agent, or Firm* — Sterne, Kessler,
Goldstein & Fox P.L.L.C.(57) **CLAIM**

The ornamental design for a camera gimbal, as shown and described.

DESCRIPTION

FIG. 1 is a top front perspective view of a camera gimbal showing the claimed design.

FIG. 2 is a front view of thereof.

FIG. 3 is a rear view of thereof.

FIG. 4 is a left side view of thereof.

FIG. 5 is a right side view of thereof.

FIG. 6 is a top view of thereof; and,

FIG. 7 is a bottom view of thereof.

The shade lines in the figures show contour and not surface ornamentation.

The broken lines in the figures show portions of the camera gimbal that form no part of the claimed design.
